UNITED STATES PATENT OFFICE

2,524,994

SNOW SKATE

Oscar Sandstedt, Elmhurst, N. Y.

Application April 30, 1946, Serial No. 666,160

2 Claims. (Cl. 280—11.13)

1

My invention relates to skates and more particularly to snow skates.

The object of my invention is to provide a skate adapted to be fastened onto a shoe and having flat runner surfaces adapted to engage and slide over the surface of a snow field.

Another object of my invention is to provide a snow skate adapted to be adjusted to fit onto a variety of shoes of different sizes.

Other objects of my invention may appear in the following specification describing my invention with reference to the accompanying drawing illustrating a preferred embodiment of my invention. It is however to be understood that my invention is not to be limited or restricted to the exact construction and combination of parts described in the specification and shown in the drawing but that such changes and modifications may be made as fall within the scope of the claims appended hereto.

In the drawing:

Figure 1 is a side elevation of a snow skate according to my invention;

Figure 2 is a top plan view of the snow skate illustrated in Figure 1;

Figure 3 is a sectional view taken on line 3—3 in Figure 1;

Figure 4 is a cross section through a modified form of a runner adapted to be used in connection with my invention; and

Figure 5 is a plan view of a blank from which the heel platform supporting bracket illustrated in Figure 3 is formed.

Referring now in detail to the drawing the snow skate according to my invention has a runner 10 which is preferably made from sheet steel of any suitable gauge by stamping. The runner 10 has two flat runner faces 11 connected with each other by means of an elevated middle portion 12 having a cross section shaped like an inverted U. The main portion of the runner 10 extends horizontally, but the forward portion 13 is curved upwardly as clearly shown in Figure 1. Extending over the entire length of the outer edges of each runner face 11 a crimp flange 14 is arranged which extends downwardly and outwardly from the runner face, as shown in Figure 3.

A front shoe plate 15 has a flat main portion 16, from which a tongue 17 extends forwardly and downwardly to meet the curved runner portion 13, to which it is fastened by means of a countersunk rivet 18.

Adjacent the rear rim of the shoe plate portion 16 and located on the longitudinal center line thereof a circular depression 19 is formed reaching down to the elevated middle portion 17 of the

2

runner 10 to which it is fastened by a countersunk rivet 20.

It is to be understood that the shoe plate 15 can be fastened in any different conventional and desired manner to the runner, for instance by welding.

Adjacent the rear end of the runner 10 a heel plate 21 is adjustably attached to the runner 10. This heel plate has a substantially flat heel supporting platform 22 on the rear of which a curved upwardly and rearwardly extending flange 23 is integrally formed. This heel plate 21 is supported by a bracket 24 comprising a slotted metal strip 29 having at each end an inclined tongue 25 the outer, apertured ends of which rest upon elevated middle portion 12 of the runner 10 and are secured thereto by suitable countersunk rivets. One of the tongues 25 extends forwardly and downwardly and the other rearwardly and downwardly.

Two flanges 26 are bent inwardly from each tongue of the bracket 24 to rest on the middle portion of the runner 10 between the tongues.

Two rounded beads 27 are formed on the longitudinal top edges of the bracket 24 and two elongated depressions 28 are formed in the heel plate 21 so that they are located slidably outside of the beads 27.

The heel platform 21 has a round dent 32 with a central hole therein, which hole receives a machine screw 33 which extends through the hole in the dent 32 and through the slot 31 in the top strip 29 of the bracket. A nut 34 on the machine screw 33 is adapted to secure the heel plate in any adjusted position on the bracket 24.

When the heel plate 21 is moved forwardly or rearwardly to adjust the snow skate to the size of the shoe, the beads 27 and the depression 28 serve as guides to keep the heel plate in line.

In order to permit the use of leather straps (not shown) to fasten the snow skate onto a shoe two slots 35 are provided in the flange 23 on the heel plate 21 and two strips 36 of metal are depressed in the shoe plate 16 forming passages 37 for leather straps or the like.

The modifications of the runner 10a shown in Figure 4 is formed substantially the same as described above with reference to runner 10. It has an elevated middle portion 12a and two flat runner faces 11a, but the longitudinal crimp flanges 14a on the outside edges of the runner extend outwardly and upwardly in this modification.

Having described my invention I claim as new and desire to secure by Letters Patent:

1. A snow skate adapted to be fastened to a shoe, said skate including a runner comprising

two longitudinal runner faces and an elevated middle portion connecting the two runner faces with each other, a shoe plate rigidly fastened to said elevated middle portion of the runner adjacent its forward end, a heel platform, a bracket rigidly mounted on the said elevated middle portion of the runner adjacent its rear end for adjustably supporting said heel platform, said bracket comprising an elongated strip having a longitudinal slot therein, inclined tongues disposed one at each end of said strip and secured at their outer ends to said elevated middle portion of said runner, longitudinal beads on said strip disposed one at each side of said slot, said heel platform having longitudinal depressions therein disposed respectively at the outer sides of said beads and slidably engaging the same and an apertured dent therein between said depressions, a screw extending through the apertured dent in said heel plate and the slot in said bracket, and a nut on said screw to adjustably secure said heel platform to said bracket.

2. A snow skate adapted to be fastened to a shoe, said skate including a runner comprising two longitudinal runner faces and an elevated middle portion connecting said two runner faces with each other, a shoe plate rigidly fastened to said elevated middle portion of the runner adjacent its forward end, a heel platform, a bracket rigidly mounted on the elevated middle portion 30

of the runner adjacent its rear end for adjustably supporting said heel platform, said bracket comprising an elongated strip having a longitudinal slot therein, longitudinal beads disposed one at each side of said slot, inclined tongues disposed one at each end of said strip and secured at their outer ends to the elevated middle portion of said runner, and a pair of flanges extending inwardly from each tongue and resting upon said elevated middle portion between said tongues, said heel platform having longitudinal depressions therein respectively disposed at the outer sides of said beads and an apertured dent therein slidably disposed between said beads, a screw extending through said apertured dent and the slot in said bracket, and a nut on said screw adjustably securing said heel platform to said bracket.

OSCAR SANDSTEDT.
